(57) **CLAIM**

The ornamental design for a surgical device, as shown and described.

DESCRIPTION

FIG. 1 is a front perspective of a surgical device according to my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines immediately adjacent the claimed areas in FIGS. 1-7 represent the bounds of the claimed design while all other broken lines represent environmental structure and are for illustrative purposes only; the broken lines form no part of the claimed design.
